REST OR SUPPORT FOR CIGARETTES AND CIGARS

Martin F. Connellan, Pasadena, Calif.

Application August 6, 1947, Serial No. 766,730

3 Claims. (Cl. 131—257)

1

This invention relates generally to smoker's equipment or accessories and is directed particularly to improvements in rests or supports for cigarettes and cigars.

In the usual cigarette and cigar ash tray means is provided for the support of the cigarette or cigar when the smoker desires to put the same down for a few minutes, such support frequently being in the nature of a groove or recess formed across the rim of the ash tray or a short post or pedestal mounted on the rim of the ash tray and carrying a curved or channelled plate in which the cigarette, or cigar, is placed. With supports of this character cigarette or cigars continue to burn and not infrequently burn to a point where the outer end of the cigarette or cigar over balances the inner end so that the burning body falls off on to the table or floor.

It is an object of the present invention to provide a support for the cigarette wherein the latter when laid down will have a covering element disposed over it so that it cannot be knocked off, such cover element also functioning to extinguish the cigarette when the lighted end has burned down to the inner edge of the support upon which the cigarette rests.

Another object of the invention is to provide a device of the character stated which includes a fixed bottom portion having a substantially semi-circular groove or recess therein and in which the cigarette is placed, and a movable top or weight element which is pivotally attached to the bottom section and which has a semi-circular recess designed to match the recess in the bottom section to form a cylindrical or tubular passage in which the body of the cigarette is retained, such pivoted weighted portion functioning to hold the cigarette in place and also to extinguish the same when the lighted end has burned into the passage in which the cigarette is housed.

Still another object of the invention is to provide a rest or support for a cigarette or the like, as above described, wherein means is provided for automatically effecting the closing of the weighted top portion over the body of the cigarette as the cigarette is placed in position in the recess in the bottom portion.

The invention will be best understood from a consideration of the following detailed description taken in connection with the accompanying drawings forming a part of the specification, with the understanding, however, that the invention is not to be understood as limited to the exact details of construction shown and described since obvious modifications will occur to a person skilled in the art.

2

In the drawing:

Figure 1 is a view in elevation of a cigarette holder constructed in accordance with an embodiment of the present invention.

Figure 2 is a view similar to Figure 1 but showing the weight member raised.

Figure 3 is a view in top plan of the device shown in Figure 1.

Figure 4 is a vertical section taken substantially on the line 4—4 of Figure 1.

Figure 5 is a view in perspective of an ash tray showing the invention as a part thereof.

In describing the function of the present invention reference will be made only to the use of a cigarette in association therewith in view of the fact that cigarettes are more commonly smoked than cigars and also to avoid unnecessary repetition but it will be understood that wherever the word "cigarette" is used in describing the use of the invention it will be understood that cigars or other similarly formed "smokes" are included.

The present invention may form a part of a pocket element or it may be incorporated with and form a part of a conventional ash receptacle.

25 In the drawings, Figures 1 to 4 illustrate the invention embodied in a pocket form whereby it may be carried about for use by a smoker. In this form there is illustrated a base portion 10 which comprises a block of metal or other suitable material having a flat bottom wall 11 whereby it may be placed upon a table or other supporting surface. This block or base portion 10 may be made of any desired length and thickness and the top face or surface 12 is provided with transverse substantially semi-circular channel or recess 13 of the proper size to snugly receive a cigarette.

30 The numeral 14 generally designates a weight body which may be formed of the same material as the bottom portion 10 and it may also be of the same general configuration whereby the under face 15 may rest flat upon the top face 12 of the base or bottom body 10. While the top design or configuration of the weight body 14 may be as preferred it is shown as stepped back at its two ends providing the terraced portions 16 whereby a modernistic design is given to the weight.

35 One end of the weight body 14 is pivotally attached to the supporting block body by a suitable hinged connection as indicated generally at 17. This hinge connection as here illustrated comprises a hinge ear 18 which is formed integrally with the top of block 10 at one end of the block and extends upwardly from the face 12, and the

pair of spaced ears 19 which form a longitudinal end extension of the weight body 14 and have the ear 18 positioned therebetween. The ears 18 and 19 have aligned bores 20 formed therethrough and transversely of the device to receive the pintle pin 21. Thus it will be seen that the weight body 14 is hingedly attached to an end of the base or bottom of block 10 so that it may be swung from a position where it is superimposed upon the top of the base block to a raised vertical position as is shown in Figure 2.

The under face 15 of the weight body 14 has a substantially semi-circular groove or recess 22 formed transversely thereacross and of the same radius as the groove or channel 13 and in a position where it will match concentrically with the channel 13 when the weight body is in lowered position thereby forming a completely circular passage or bore of a diameter to snugly receive the body of a cigarette.

One end of the pintle 21 has an integral right angularly extending portion 24 which lies across the outer side of the adjacent ear 19 and this is formed integral with the terminal portion 25 which is parallel with the pintle and extends across a terrace portion 16.

The opposite end of the hinge pintle 21 is connected with the right angularly extending relatively long bar 26. This bar forms an obtuse angle with the portion 24 at the opposite end of the hinge pintle. The angular relation between the bar 26 and the portion 24 of the pintle is such that when the weight body is swung to opened position as shown in Figure 2, where it will lean slightly from the perpendicular away from the remote end of the base block 10, the bar 26 will be elevated to a position substantially in the plane of the top surface 12 where its free end will extend across the channel 13.

When the smoker desires to rest the cigarette in the support and places the lighted end in the recess 13 this action will effect the depression of the free end of the bar 26 and tilt or cant the weight body 14 to a position where it will fall by gravity horizontally on the top 12 of the base body. The lighted end of the cigarette will then be caught or clamped between the two bodies in the passage 23 formed by the semi-circular recesses 13 and 22 and if allowed to remain for any length of time so as to burn down to the end of the passage 23 it will be snuffed or put out and in addition it will be securely held so that it cannot fall out of place.

Figure 5 illustrates the application of the invention to a conventional type of ash tray which is generally designated 10a. The side or rim of this ash tray corresponds to the base block 10, having formed therein and transversely thereof a semi-circular recess 13a corresponding to the recess 13. Upon the top of the rim of the ash receptacle the weight block 14a is pivotally attached by the hinge pintle 21a. The inner end of this pintle is attached to the right angularly extending bar 26a which functions in the same manner as the bar 26, in that it extends across the upper part of the recess 13a when the weight body 14a is raised.

It can readily be seen that whether the invention is made a part of an ash tray or is in a form where it may be conveniently carried in the pocket the operation is the same. Accordingly, it is believed to be unnecessary to go into a more detailed description of the construction and operation of the weight body 14a as this is the same as the body 14.

It is pointed out that a particularly advantageous feature of the present invention is in connection with its use upon moving bodies such as automobiles, yachts, planes, etc. where the vibration or movement of the vehicle would tend to jar a cigarette or cigar from a holder of the usual or ordinary type whereas in the present invention the cigarette or cigar would be firmly held and no amount of jarring or swaying would cause it to fall from its support.

To facilitate the raising of the weight member or top 14 use may be made of an upstanding member such as that illustrated and designated 27. As will be readily apparent when such a member is made a part of the weight body the weight body may be easily lifted by moving the side of the hand against the member 27 or by grasping such member with the fingers. Also, if desired, the member 27 may be of suitable form or shape to receive printed matter for advertising purposes and the like. For example, such member 27 may be in the form of a keystone, the same being the symbol used by and as identifying a particular railroad system. Other organization might make use of similarly formed members which would serve the double function of a means for facilitating the raising of the weight body and also for advertising or identifying the organization putting out the cigarette holder or using the same.

I claim:

1. A support for a lighted cigarette or the like, comprising a base body having a top surface of a width materially less than the length of the cigarette, said top surface having a semi-circular recess formed transversely therein to receive the lighted end of the cigarette, a weight body adapted to position upon said top surface, a hinge connection between the weight body and the base whereby the weight body may be swung upwardly from the top surface, said hinge including a pintle pin, said weight body having an under face provided with a semi-circular recess transversely thereof and of the same radius as the first recess, said semi-circular recesses being joined upon the swinging of the weight body down to rest upon the top surface of the first body to form a circular cigarette holding passage, and a bar forming a right angular extension of one end of the pintle and movable with the weight body to assume a position across an end of the recess in the base body when the weight body is raised and to swing downwardly below the first mentioned recess when the weight body is lowered.
2. A support for a lighted cigarette comprising a body having a top surface provided with a recess of a length less than the length of a cigarette and in which the cigarette may be placed, a weight body designed to be positioned upon the first body across said recess, said weight body having a transverse recess to coincide with the recess of the first body to form a tubular receiver in which the cigarette is secured, a pivot coupling between the two bodies at one side of the recesses, and an element connected with the weight body and adapted to move in a position across an end of the recess in the first body when the weight body is in raised position and to swing downwardly away from the recess of the first body when the weight body is swung down into closed position.
3. A support for a lighted cigarette, comprising a base body having a top provided with a cigarette receiving recess, a movable weight body having a closed position in which it lies on said

top across the recess, the weight body having a recess which coincides with the first recess when the weight body is in closed position to form a tubular enclosure for a portion of a cigarette, a hinge coupling the weight body with the base at one side of the recesses to swing on an axis substantially paralleling the recesses, the weight body having an open position in which it stands substantially upright from the hinge, the weight body swinging freely to its closed position by the action of gravity when it is shifted to a predetermined extent in one direction from said open position, and a lever bar secured to the weight body to position across the first recess above the level of the bottom thereof when the weight body is in said open position, said lever moving to a position below the level of the bottom of the first recess when the weight body is moved to its closed position.
